COMBINATION STORM AND DOOR FRAME

John L. Holberton, 34846 Goddard, Romulus, Mich.

Filed Mar. 31, 1959, Ser. No. 55,273

Term of patent 14 years

(Cl. D13—1)

FIG. 1 is a front elevational view of the combination storm and screen door frame embodying my new design.

FIG. 2 is an enlarged fragmentary sectional view of the structure illustrated in FIG. 1, taken along the line 2-2 thereof; and

FIG. 3 is an enlarged fragmentary sectional view of the structure illustrated in FIG. 1, taken along the line 3-3 thereof.

I claim:

The ornamental design for combination storm and screen door frame, as shown.
